UNITED STATES PATENT OFFICE.

FRANK JANAK, OF WOODLAND, CALIFORNIA.

WAGON-BED HOIST.

1,201,969.

Specification of Letters Patent. Patented Oct. 17, 1916.

Application filed April 9, 1915. Serial No. 20,304.

To all whom it may concern:

Be it known that I, FRANK JANAK, a citizen of the United States, residing at Woodland, in the county of Yolo and State of California, have invented certain new and useful Improvements in Wagon-Bed Hoists; and I do hereby declare the following to be a full, clear, and exact description of the invention, such as will enable others skilled in the art to which it appertains to make and use the same.

This invention relates to a device for removing beds from wagons or like vehicles, and the primary object of the invention is to provide a device as specified by means of which a wagon bed may be quickly and easily removed from a wagon with a minimum amount of manual exertion.

Another object of this invention is to provide a device for removing beds from wagon running gears which includes a pair of pivotally supported rails, means for limiting the pivotal movement of said rails, and means for holding the rails in a horizontal wagon bed supporting position.

With the foregoing and other objects in view this invention consists in such novel features of construction, combination and arrangement of parts as will be hereinafter more fully described, illustrated in the accompanying drawings and claimed.

In describing the invention in detail, reference will be had to the accompanying drawings wherein like characters designate like or corresponding parts throughout the several views, and in which:

Figure 1 is a side elevation of the improved wagon bed remover, showing it in a position for receiving a wagon bed, Fig. 2 is a side elevation of a wagon bed remover, showing it in a wagon bed supporting position, Fig. 3 is a top plan view of the bed hoist, Fig. 4 is an end view of the bed hoist, Fig. 5 is a longitudinal section through the hoist, and Fig. 6 is a cross section on the line 6—6 of Fig. 2.

Referring more particularly to the drawings, 1 designates the supporting base of the wagon hoist, which has standards 2 and 3 secured thereto, which standards have their upper ends rounded, as is shown at 4, for rockably supporting wagon bed supporting rails 5 and 6. The rails 5 and 6 have transversely extending cleats 7 secured to their under surfaces, and have plates 8 secured to their side edges, which cleats and plates

form sockets for receiving the upper curved ends of the standards 2 and 3. The rails have their under surfaces, at the point which engages the upper curved ends of the standards, slightly cut away to form concave surfaces 10, which rest upon the upper ends of the standards, as is clearly shown in Fig. 5 of the drawings.

The supporting base 1 has standards 11 and 12 secured thereto outwardly of the standards 2 and 3. The standards 11 and 12 have a section of their rear or inner edges cut away, forming shoulders 14 which are provided for receiving the lower recessed ends of pivoted dogs 15 and 16, which are pivotally connected to legs 17. The legs 17 are secured to the rails 5 and 6 adjacent their forward ends and extend downwardly at an incline therefrom, having cross bars 18 connecting their lower ends. The outer legs 17 have locking pawls 19 and 20 pivotally connected thereto, which are provided for engagement with pins 21 that are carried by the pivoted dogs 15 and 16 and extend transversely therefrom. The pawls 19 and 20 have their ends, which engage the pins 21, curved convexly and concavely, to provide an arcuate surface which will ride over the pins during the movement of the rails 5 and 6, until the ends 22 of the pawls engage the pins, which prevent pivoted movement of the dogs 15 and 16 and consequently rocking the pivoted movement of the rails 5 and 6.

The standards 11 and 12 have flexible members 23 secured thereto, which flexible members are in turn connected to substantially U-shaped bail members 24 which are pivotally connected to the sides of the outer ends of the rails 5 and 6. The vertexes of the U-shaped members 24 are provided with humps or outstruck portions 25, to which the flexible members 23 are connected. The flexible members 23 form means for limiting the upward movement of the rails.

When it is desired to remove a wagon bed from a wagon, the wagon is driven between the rails 5 and 6, which rails have their forward ends positioned downwardly, as is shown in Fig. 1 of the drawings. The section of the wagon bed which projects outwardly over the wheels, rides upon the upper surface of the rails, and after a section of the bed has passed the pivoted point of the rails, the rails may be tilted to a horizontal position with very little effort, which

will remove the bed from the wagon running gears and permit the latter to be drawn from between the rails without the bed. When the rails 5 and 6 are moved into a horizontal position, the pivoted dogs 15 and 16 will, of their own weight, swing rearwardly and engage the shoulders 14, for preventing the accidental downward movement of the rails. When it is desired to remove the bed from the rails, the pivoted pawls 19 are moved for forcing the dogs 15 rearwardly upon their pivotal points, positioning their lower recessed ends out of the path of the shoulders, thereby permitting the rails to be tilted downwardly for depositing the wagon bed upon the running gears.

In cases where it is desired to remove a bed from a wagon, wherein the bed does not project laterally of the running gears of the wagon, bars may be positioned beneath the bottom of the bed and extend laterally upon each side of the bed for seating upon the tops of the rails.

If it is so desired, the supporting base 1 may be eliminated, and the various standards embedded in the ground.

From the foregoing description taken in connection with the accompanying drawings the advantages of construction and of the method of operation of the improved wagon bed hoist will be readily apparent to those skilled in the art to which this invention appertains, and while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

1. In a device as set forth, a plurality of standards having their upper ends rounded, a plurality of rails having recesses in their under faces mounted upon the rounded ends of said standards, plates carried by said rails, said plates and recesses forming bearings for receiving the rounded ends of said standards, legs secured to the outer ends of said rails for limiting the downward pivotal movement, a plurality of standards having a section of their rear edges cut away for forming horizontal shoulders, and dogs pivotally carried by said legs for engage-

ment with said shoulders for holding said rails in horizontal wagon bed supporting position.

2. In a device as set forth, a plurality of standards having their upper ends rounded, a plurality of rails having recesses in the under faces thereof and mounted upon the rounded ends of said standards, plates carried by said rails, and surrounding the upper ends of said standards, said plates and recesses forming bearings for receiving the rounded ends of said standards, legs secured to the outer ends of said rails for limiting the downward pivotal movement, a plurality of standards having a section of their rear edges cut away for forming horizontal shoulders, dogs pivotally carried by said legs for engagement with said shoulders for holding said rails in horizontal wagon bed supporting position, flexible members connected to said second named standards and said rails for limiting the upward pivotal movement of said rails.

3. In a device as set forth, a base, standards arranged in pairs and formed integrally at their lower ends with the base, said standards having their upper ends rounded, a plurality of rails having their under sides provided with recesses and mounted upon the rounded ends of said standards, plates carried by said rails and depending below the under surface thereof and surrounding the upper ends of the standards, said plates and recesses of the rails forming bearings for receiving the rounded ends of said standards and preventing any lateral movement of the rails upon the standards, legs secured to the outer ends of said rails for limiting the downward pivotal movement thereof, a plurality of standards having sections of the rear edges cut away forming horizontal shoulders, dogs pivotally carried by said legs for engagement with said shoulders for holding said rails in a horizontal wagon bed supporting position, and flexible members connected to said second named standards and the ends of said rails for limiting the pivotal movement of said rails upon the first named standards.

In testimony whereof I affix my signature in presence of two witnesses.

FRANK JANAK.
